UNITED STATES PATENT OFFICE.

JOHN A. LUDWIG AND JACOB B. MOSES, OF DALLAS, TEXAS.

TROUSERS.

1,071,932.

Specification of Letters Patent.

Patented Sept. 2, 1913.

Application filed September 3, 1910. Serial No. 580,282.

To all whom it may concern:

Be it known that we, JOHN A. LUDWIG and JACOB B. MOSES, citizens of the United States, residing at Dallas, in the county of Dallas, State of Texas, have invented new and useful Trouzers, of which the following is a specification.

This invention relates to trousers and it consists in the novel construction and arrangement of its parts as hereinafter described and shown.

The object of the invention is to so construct a pair of trousers that the waist portion thereof may be readily manipulated in order that the trousers may be easily converted from a stock size into a pair of trousers having a high waist band, a low waist band or a waist band at a line between high and low.

One great difficulty in dealing in ready-to-wear trousers at the present time is to get them exactly the height in the waist that the customer desires. From experience it has been found that at least four pairs of trousers in every ten that are made ready to wear, particularly those which go with suits, are too high in the waist. This is especially true during the summer season when suspenders are usually discarded and belts substituted. To lower the waist band of a pair of trousers the way they are now constructed is a tedious time consuming alteration, and even if successful, in so far as the fitting quality is concerned, the change usually leaves the trousers in an unsightly condition, and consequently are displeasing to those who are particular about dress.

Therefore it is the object of the present invention so to construct the trousers that they may readily be converted from high waist trousers to low waist, and from low waist to high waist or very high, without affecting their harmony. The way the trousers are constructed renders it possible for an ordinary tailor to make the desired alteration. In fact, the operation of conversion from low to high, and from high to low is so simple that any one who has an idea of sewing can do the work. It requires but a few moments to effect the change of the position of the waist band.

In the accompanying drawing:—Figure 1 is a perspective view of the upper portion of one form of trousers. Fig. 2 is a sectional view cut on the line 2—2 of Fig. 1. Fig. 3 is a sectional view cut on the line

3—3 of Fig. 1. Fig. 4 is a sectional view cut on the line 4—4 of Fig. 1. Fig. 5 is a sectional view cut on the line 5—5 of Fig. 1. Fig. 6 is an inside view of a portion of the upper part of the trousers, with parts turned back. Fig. 7 is an inside view of a modified form of the upper portion of a pair of trousers.

The general pattern of the pieces of the trousers, except in the vicinity of the waist, is not changed or altered from that in common use.

In the present structure the waist band usually employed in trousers is eliminated and the side pieces of the trousers are continued and formed into a flap 1 which in low waist trousers is turned down upon the inside, as indicated in the several figures. The flap 1 may be provided at its edge with a taping 2 or in lieu thereof, any other form of trimming may be applied. Belt straps 3 are attached to the upper edge portion of the trousers at suitable intervals and are of sufficient length that at one end they may terminate in the vicinity of the edge of the flap 1 and at the other end at some distance below the upper edge of the trousers when they are adjusted in low waist form.

In the form of the invention as illustrated in Figs. 1 and 3, suspender buttons 4 are sewed to the flap 1 upon the side thereof which is innermost when the flap is turned down, the same side being outermost when the strap is extended in an upward direction. The back pieces 5 of the trousers are sewed directly together at the back seam in the usual manner but are not bridged at their upper portion by a lining, as is the usual custom. Each back piece 5 is provided with a lining section 6 which terminates at the edge portion of the back piece to which it is applied. Hip pockets 7 are provided in the back pieces 5 in the usual manner and the lining sections 6 connect at their forward edges to pockets 8 which are attached to the rear edges of the front pieces 9 of the trousers.

The lower ends of the mouths of the side pockets 8 are closed at the side seams 10 by tacks 11 and the upper ends of the mouths of the side pockets 8 are closed by tacks 12. These tacks 12 are at the rear edges of the front pieces 9 and the forward edges of the back pieces 5. The watch pocket 13 is so positioned that it may be conveniently used whether the trousers be in the form of high,

low or medium waist. The fly lining 14 is provided with a button hole 15 with which a button hole 16 registers when the flap 1 is turned down in the manner as indicated 5 in Fig. 6 of the drawing so that the button on the opposite side of the fly passes through both button holes thereby holding the waist band against the trousers and assuring comfort to the wearer. At the upper end of the 10 back seam of the trousers the back pieces 5 are held together by the tacks 17 and above the said tacks the said side pieces diverge away from each other and in the V thus formed a piece may be inserted for increasing 15 the girth of the trousers.

In the form of the trousers as illustrated in Fig. 7, the general arrangement hereinbefore described has been followed except that the suspender buttons 4 are attached 20 to the flap 1 upon that side thereof which is innermost when the flap is extended and the fly 18 is provided at its upper end with a tab 19 which is in alinement with the end of the flap 1 proper and is adapted to be 25 turned down with the same when the trousers are converted into low waist form. By providing the tab 19 at the upper end of the fly 18, a more substantial foundation is afforded for the button which is usually 30 located at the upper end of the fly and thus when the trousers are converted into high waist form there will be no chance for the material to gap at the upper edge of the fly. In this form of trousers when they are 35 converted into the high waist form, the suspender buttons 4 are concealed from view. This is by reason of the fact that the buttons are upon the inner side of the flap 1 when the flap is extended.

40 In Fig. 1 the trousers are shown in low waist form. The parts being in the positions as illustrated and it being the desire to convert the trousers into medium or high waist form, the lower edge of the flap 1 is 45 disconnected from the side and back pieces of the trousers and is extended wholly or partially in an upward direction. The tacks

11 and 12 are moved so that the mouths of the side pockets 8 may be at appropriate distances below the upper edge of the trousers. Also the belt straps 3 may be readily moved and superfluous lengths cut off or turned under as desired. Therefore it will be seen that during the process of transposing the waist of the trousers it is not necessary to disturb the lining sections 6 or their 50 connections with the back pieces 5 and side pockets 8, and thus the harmony of the garment is not disturbed by the apparent alteration. Further the change may be quickly 55 accomplished by an unskilled person, for the reason that it is necessary only to alter the lining sections or to disconnect entirely the edge of the flap 1 from the pieces of the trousers, and remove or re-position the belt 60 strap 3 at the upper edge thereof.

Having described the invention, what is claimed is:

A pair of trousers having a waist band constituting an integral continuation of and 70 of the same thickness as the body of the garment and provided with a crease to permit the band to be folded inwardly, lining sections secured to the inner portion of the trousers and to which the waist band is temporarily attached and from which it may readily be disconnected and turned outward to convert the garment from a low to a high 75 waist article, said waist band and lining each being provided with an opening adapted to register when the band is folded inwardly to receive a fastener, and suspender-engaging means secured to the band.

In testimony that we claim the foregoing as our own, we have hereto affixed our signatures in the presence of two witnesses.

JOHN A. LUDWIG.
JACOB B. MOSES.
